HYDRAULIC PUMPING SYSTEM

William W. Kurns, Crystal Lake, Ill., assignor to The Amco Corporation, Chicago, Ill., a corporation of Illinois

Application January 24, 1957, Serial No. 636,103

7 Claims. (Cl. 137—267)

This invention relates to hydraulic pumping systems; to a hydraulic system for selectively discharging liquids from any one of a plurality of vehicle mounted tanks; and to a unique closed pumping system which is readily mountable on any truck vehicle, and which is adaptable to operate any number of pumping and hose reel units, all of which are hydraulically driven from a single source of power.

Present day local distribution of gasoline and oil products is accomplished chiefly by means of large motor vehicles in the form of trucks or tractor-trailer combinations having multi-tank installations for carrying a variety of products. In order to prevent mixing of the different oil and gasoline products, a separate independent system, including a hose and product pump, is connected with each product tank. In passing, it is to be noted that most communities have passed laws requiring a separate discharge system for each product tank, thereby eliminating the possibility of explosions resulting from instances where highly volatile gasoline products, left in the pumps and hoses, are dispensed along with oil to apparatus designed to burn only oil products.

In the art, many systems have been devised for discharging the liquid products from product tanks. Commonly used apparatus for driving the product pumps includes the employment of a set of rigid shafts interconnected by universal couplings, the shafts being connected at one end to their respective product pump and at their other end to a power take-off from the vehicle's transmission. Often, flexible drive shafts are substituted for the rigid shafts. In many instances, it is found that truck framework must be cut to allow the shaft to pass therethrough, thereby appreciably weakening the frame, or, in still other instances, that the product pumps cannot be mounted at the most advantageous locations since it is impossible to extend the shafts thereto. Whether rigid or flexible shafts are used, however, the resulting set-up for driving the product pumps is a maze of shafts which are laborious and expensive to install, difficult to disassemble and repair, noisy in operation, and require close maintenance.

Even those few known systems for driving the product pumps hydraulically have not given full satisfaction. These systems are not easily adaptable to accommodate any number of product tanks and, more often than not, provide no safety arrangements for assuring that only one tank at a time can have its contents discharged therethrough. Moreover, they either have no means for automatically reeling in each product hose, or they provide an independent electric motor for driving each hose reel. The use of electrical motors around highly volatile gasoline products, of course, is not desirable, since there always is the danger of a spark causing a fire or explosion.

In contrast, the present invention contemplates the provision of a completely hydraulic system for driving both product pumps and hose reels, the system being adaptable for mounting to both existing and new trucks and tractor-trailer combinations, and capable of selectively

2

driving any number of product pump and hose reel combinations.

Objects of this invention include the provision of a hydraulic system for selectively driving both product pumps and hose reels; an arrangement whereby a single hydraulic pump provides all the necessary power for selectively driving oil and gasoline product discharge units; a pumping system which may be easily detached and remounted on other motor vehicles and trucks; and a pumping system which is economical to manufacture, install and maintain, and silent in operation.

Another object of this invention is the provision of a unique arrangement whereby each product tank has its own hydraulically driven pump for dispensing its liquids, and further has its own hose and hydraulically driven reel for winding the hose, the pumps and reels of all tanks having a common source of hydraulic power.

Specifically, an object of this invention is to provide a selector valve for the pump and reel of each tank, whereby at any time only the pump or the reel can be hydraulically driven. In carrying out this provision, the invention further includes an arrangement of selector valves for all tanks, whereby no more than one tank at a time can have its contents discharged therefrom, or whereby in fact only one unit, whether a pump or a hose reel unit, can be hydraulically driven at any one time.

The objects and features mentioned and implied from the foregoing discussion are achieved by the present hydraulic pumping system and mainly by the following features of the same, it being understood, of course, that all parts herein described are suitably mounted to the frame or body of an automotive vehicle. A hydraulic pump is suitably coupled to the transmission of the vehicle, the pump intake being connected to a hydraulic fluid reservoir, and its discharge being connected with lines leading to the hydraulic motors of the units to be driven. Each tank has its own product pump and hose reel units, and each product pump and hose reel is driven by an independent hydraulic motor connected with the master hydraulic pump. Control of the flow of the hydraulic fluid is achieved by selector valves, there being one valve for each tank and its respective units, whereby either the hydraulic motor of the product pump or the hydraulic motor to drive the hose reel mechanism may be selectively run. Suitable connecting lines and headers are provided so that the hydraulic fluid flows from the selectively operating hydraulic motor back to the reservoir tank which has sufficient capacity to supply the fluid through the lines to any of the hydraulic motors. The selector valves are so arranged and interconnected that only one hydraulic motor at a time can be operated, and further are designed to allow the master hydraulic pump to run idly without operating any of the hydraulic motors of the product pump or the hose reel units.

The foregoing and other objects, advantages and features of construction will become more apparent from a consideration of the following description and the appended drawing.

In the drawing:

Figure 1 is a flow sheet representation of the pumping system embodying the present invention.

While the hereinafter description principally refers to a hydraulic pumping system employed for dispensing oil and gasoline products from vehicle mounted product tanks, it is to be understood that this is done for the purpose of illustration and that the system may be used equally as well for selectively pumping any liquid from any one of a plurality of tanks, whether vehicle mounted or not.

Referring to the drawing, the master hydraulic pump 11 is coupled to the transmission 12 of the truck by a suitable single power take-off arrangement 13. Fluid leaves pump 11 through a discharge or pressure line 14, and is

delivered to the pump through an intake line 15 leading from a hydraulic fluid reservoir tank 16.

Each product tank 10 is provided with its own product discharge apparatus. In the illustrated embodiment of the invention two such sets of apparatus are provided, although it is to be understood that the invention is capable of providing any number of such sets equal to the number of product tanks mounted to the vehicle. Each of the product pumps 17, 17a, respectively is driven by its own hydraulic motor 18, 18a, through appropriate couplings 19, 19a. The liquid product to be dispensed is supplied to the pumps 17, 17a, through the respective intakes 20 and is discharged to the product hoses through passages 21. The product discharge apparatus for each tank further includes hose reels 22, 22a, each respectively rotatably driven by an independent hydraulic motor 23, 23a.

Control of the flow of the hydraulic fluid in pressure line 14 to the various hydraulic motors is achieved by selector valves 24, 24a. Each valve includes an intake port 25, three discharge ports 26, 27, 28, and an operating handle 29 for adjusting the valve mechanism to selectively direct the flow of the hydraulic fluid from any discharge port. Such valves are well known in the art and need not be discussed in detail. One preferable embodiment of the valves is model Number 22603-1 manufactured by Webster Electric Company of Racine, Wisconsin.

Intake port 25 of valve 24 has pressure line 14 connected thereto, while discharge port 26 of valve 24 is connected with the intake 30 of product pump hydraulic motor 18 by means of line 31. Hydraulic fluid is distributed from discharge port 27 of valve 24 to the intake 32 of hose reel hydraulic motor 23 by means of line 33. When neither of the hydraulic motors 18, 23, is being run, fluid is directed from discharge port 28 of valve 24 and into line 34 connected with intake port 25 of valve 24a. The discharge ports 26, 27, of valve 24a respectively are connected through lines 35, 36, to the respective intakes 37, 38, of hydraulic motors 18a, 23a, to direct the selective flow of hydraulic fluid thereto. Discharge port 28 of valve 24a is connected to a return header 39 whereby to the respective discharge sides of the hydraulic motors 18, 18a, 23, 23a, are connected. Header 39 empties through line 40 into reservoir 16, wherefrom the drive fluid flows through line 15 to master hydraulic pump 11.

Any product pump or hose reel unit may be selectively run by the foregoing system by properly setting its respective selector valve. To deliver any product from its tank, an operator first activates the selector valve engaging the product pump hydraulic motor. The operator can then unwind the correct hose from its hose reel unit, this operation normally being accomplished by pulling the hose from the reel by hand, and sets the hose for delivery of the liquid product into its receiving tank. The desired product pump is then automatically hydraulically operated when the operator opens the nozzle allowing the product to flow through the hose into the receiving tank. After the desired amount of liquid has been delivered through the hose to the receiving tank, the operator closes the nozzle and sets the selector valve on rewind, thus activating the hydraulically driven hose reel unit to rewind the hose on its reel.

In greater detail, assuming that product pump 17 is to run, selector valve 24 is set to deliver the drive fluid from pressure line 14, through valve discharge port 26 and into line 31 to actuate hydraulic motor 18, from where the hydraulic fluid returns to header 39 for flow back to its reservoir 16. At the completion of the product delivery, either the system is disconnected from the truck transmission 12, or selector valve 24 is set to direct the fluid flow into line 34 for return to the reservoir 16. To rewind the hose, selector valve 24 is set to deliver the hydraulic drive fluid out of its discharge port 27 and into line 33 to actuate drive motor 23 and rotate reel unit 22.

Product pump 17a and hose reel unit 22a similarly may

be operated by first setting selector valve 24 to direct the fluid through its discharge port 28 and into line 34. From line 34, the fluid enters selector valve 24a for selective distribution through its discharge port to run the desired product discharge unit controlled by valve 24a.

The herein apparatus is so arranged that only one unit may be run at any time. Thus, valves 24 and 24a can direct the drive fluid through only one of their respective discharge ports to run only one of the respective product 10 pump or hose reel units they control. Further, as long as valve 24 is directing fluid through one of its discharge ports 26 or 27 to run one of its respective units, nothing which is done at valve 24a can affect the operation of the 15 operating pump or hose reel unit, since no hydraulic fluid is flowing to valve 24a. Similarly, if valve 24a is distributing drive fluid through one of its discharge ports 26, 27, to run either its respective pump 17a or hose reel unit 22a, setting of valve 24 to any setting but that which directs fluid flow to line 34 immediately cuts off the fluid 20 flow to the previously operating pump 17a or hose reel unit 22a.

The system is readily adaptable for accommodating any number of product tanks. If it is desired to connect an 25 existing system to run an additional product pump and hose reel unit, all that need be done is to reconnect discharge port 28 of valve 24a so that it directs fluid flow to a line leading into the intake of an additional selector valve, rather than having the discharge port 28 leading directly into header 39 as illustrated in the drawing. The 30 additional valve is then connected to its respective product pump and hose reel units in a manner similar to that illustrated for valve 24a. Since all selector valves are in series with each other, the same safety features will exist, that is, only one product pump or one hose reel unit in 35 the entire system can be operated at any one time.

To facilitate easy installation of the system to trucks and tractor-trailer combinations, it is preferred that the 40 hydraulic fluid transmission lines 14 and 15 be made from suitable flexible hose materials. In this manner, the master hydraulic pump 11 may be connected and disconnected to the power take-off 13 in the most expeditious way without limitation of set connecting lines to pump 11. Moreover, when the system is installed on tractor-trailer combinations, master pump 11 may be mounted 45 on the tractor near the drive transmission and the remaining apparatus may be mounted on the trailer, while the connecting lines 14, 15, allow relative movement therebetween.

From the foregoing, it readily can be seen that the 50 present hydraulic pumping system provides a maximum of versatility for use with any form of vehicle mounted multi-tank arrangements, requires a minimum of fittings, and is adaptable to accommodate any number of product tanks with only the slightest of change requirements.

It is to be understood that the apparatus shown and 55 described herein is a preferred embodiment which has been given by way of example only, and that various changes and rearrangements of the details shown may be made without departing from the spirit of the invention, 60 the scope of which is defined in the appended claims.

What is claimed is:

1. A hydraulic system for dispensing gasoline and oil products from any one of a plurality of vehicle mounted product tanks, comprising: power take-off means connected with the engine of the vehicle; a master hydraulic pump driven by said power take-off means; a product pump and a hose reel for each tank; a hydraulic motor for driving each product pump; a hydraulic motor for driving each hose reel; a hydraulic fluid circulating system connected 70 with said master pump and including a hydraulic fluid reservoir, a plurality of selector valves, one for each product tank and its corresponding product pump and hose reel units, each valve having a discharge port connected with its respective product pump hydraulic motor, 75 a second discharge port connected with its respective

hose reel hydraulic motor, a third discharge port, and means for selectively directing fluid flow through any one of said discharge ports, said valves being arranged in series with hydraulic fluid conduit extending from the third discharge port of each valve to the intake of the next successive valve whereby not more than one hydraulic motor can be run at a time.

2. A hydraulic system for selectively operating hazardous fluid discharge units including a separate product pump and a separate hose reel for each of at least two product tanks mounted on a vehicle having an engine and power take-off means driven thereby, said system comprising: a separate hydraulic motor for driving each product pump; a separate hydraulic motor for driving each hose reel; a master hydraulic pump for supplying drive fluid to the hydraulic motors; a hydraulic fluid reservoir connected with the intake of said master pump; means for distributing drive fluid to any of said hydraulic motors, said distributing means including a fluid supply line connected with the discharge of said master pump, at least two control valves, one for controlling the operation of both a product pump hydraulic motor and a hose reel hydraulic motor for a corresponding product tank, each valve having a discharge port connected with the intake of a respective one of the product pump hydraulic motors, a second discharge port connected with the intake of a respective one of the hose reel hydraulic motors, a third discharge port, an intake port, and a control for directing fluid flow through any one of said discharge ports, the intake port of one of said valves being connected with said supply line and its third discharge port being connected with the intake port of the other of said valves whereby said valves are connected in series, said distributing means further including a common return header connected with the discharges of said hydraulic motors and the third discharge port of said other valve, and leading into said reservoir whereby a closed circuit is provided for said hydraulic fluid.

3. A hydraulic system for dispensing oil products from any one of a plurality of vehicle mounted product tanks, comprising: a power take-off connected with the vehicle engine; a master hydraulic pump driven by said take-off means; a plurality of product pumps, one for each product tank; a plurality of hose reel units, one for each product tank; a plurality of hydraulic motors, each for driving a respective one of said product pumps; a second plurality of hydraulic motors, each for driving a respective one of said hose reel units; a plurality of valves, each for controlling the selective operation of both a respective one of the product pump hydraulic motors and a respective one of the hose reel unit hydraulic motors; conduit connecting each product pump hydraulic motor with a discharge port in its respective valve; second conduit connecting each hose reel unit hydraulic motor with a second discharge port in its respective valve; means on each valve controlling fluid distribution from either discharge port; and further conduit connecting said valves in series with each other and with said master pump.

4. In combination with a motor vehicle having a plurality of product tanks mounted thereon, and a separate product pump and a separate hose reel unit for each product tank, a system for hydraulically operating all product pumps and all hose reel units, said system comprising: a master hydraulic pump driven by the vehicle motor, a plurality of hydraulic motors, one for driving each product pump and one for driving each hose reel unit, a plurality of valves, each for controlling the selective operation of both a respective one of the product pump hydraulic motors and a respective one of the hose reel unit hydraulic motors, conduit connecting each product pump hydraulic motor with a discharge port in its respective valve, second conduit connecting each hose reel unit hydraulic motor with a second discharge port in its respective valve, means on each valve for control-

ling fluid distribution from either discharge port, and further conduit connecting said valves in series with each other and with said master pump whereby hydraulic fluid may be selectively distributed to any of said hydraulic motors to run the product pump or hose reel unit driven thereby.

5. In combination with a motor vehicle having a plurality of product tanks mounted thereon, and a separate product pump and a separate hose reel unit for each product tank, an improved system for hydraulically operating all product pumps and all hose reel units, said system comprising: a master hydraulic pump driven by the vehicle motor, a separate hydraulic motor for driving each product pump, a separate hydraulic motor for driving each hose reel unit, hydraulic fluid circulating means connected with said master pump and including a hydraulic fluid reservoir, a plurality of control valves, one for each product tank and its corresponding product pump and hose reel hydraulic motors, each valve having a discharge port connected with its respective product pump hydraulic motor, a second discharge port connected with its respective hose reel unit hydraulic motor, and means for distributing hydraulic fluid through either of said discharge ports, and conduit connecting said valves in series with each other and with said master pump and said fluid reservoir.

6. The combination for use with a truck having an engine and power take-off means driven thereby, comprising: a pair of product tanks mounted on said truck; a pair of product pumps, each for pumping the liquid product from a respective one of said tanks; a pair of hose reel units, each for delivering the liquid product from a respective one of said tanks; a pair of hydraulic motors, each for driving a respective one of said product pumps; a second pair of hydraulic motors, each for driving a respective one of said hose reel units; a pair of selector valves, each for controlling the selective operation of both a respective one of the product pump hydraulic motors and a respective one of the hose reel unit hydraulic motors, each valve having a discharge port connected with its respective product pump hydraulic motor, a second discharge port connected with its respective hose reel unit hydraulic motor, and a selector for distributing hydraulic fluid through either of said discharge ports; a master hydraulic fluid pump driven by said power take-off; a hydraulic fluid reservoir; and conduit connecting said valves in series with each other and with said master pump and said reservoir, whereby power fluid may be selectively distributed to any one of said hydraulic motors to operate the apparatus driven thereby.

7. A hydraulic system for pumping liquids from any one of a plurality of tanks, comprising: a plurality of product pumps, one for each tank; a plurality of rotatable hose reel units, one for each tank; a plurality of hydraulic motors, one coupled to a respective one of said pumps and one coupled to a respective one of said hose reel units to drive the same; a master hydraulic pump; means for driving said master pump; a hydraulic fluid reservoir connected with the intake of said master pump; a return header connecting the discharge of said hydraulic motors with said fluid reservoir; a plurality of control valves, each controlling the selective operation of both a product pump hydraulic motor and a hose reel unit hydraulic motor, each valve having a discharge port connected with the intake of its corresponding product pump hydraulic motor, a second discharge port connected with the intake of its corresponding hose reel unit hydraulic motor, a third discharge port, an intake port and a control for selectively directing fluid flow from any one of its discharge ports; means connecting said valves in series including fluid lines extending between the third discharge ports to the intake port of the next successive valve; a fluid line connecting the intake port of the first of said series connected valves with the dis-

charge of said master pump; and a fluid line connecting the third discharge port of the last of said series connected valves with said return header.
